John E. A. Koenigsberg
ATTORNEY

UNITED STATES PATENT OFFICE

OLE O. HAUGSBAK, OF PASSAIC, NEW JERSEY

PLANE FOR PARQUET FLOORS

Application filed September 5, 1929. Serial No. 390,478.

This invention relates to improvements in planes and has particular reference to planes which are used for planing the edge of tongued boards such as are used for parquet floors and similar purposes.

The object of the invention is to provide a plane especially well adapted for planing that part of the edge of a tongued board which is below the tongue after the board has been laid. Another object of the invention is to provide such a plane of very simple and efficient design and construction and of inexpensive manufacture.

To this end the invention is embodied in a plane arranged and constructed as hereinabove set forth and as illustrated in the accompanying drawing in which—

Fig. 1 is a plan view of the plane with certain details omitted.

Fig. 2 is a side view of the plane with parts in section.

Fig. 3 is a plan view of the plane with parts omitted and showing the side opposite to the one shown in Figure 1.

Fig. 4 is a detail view showing the use of the plane.

Referring to the drawing the plane consists of a base or body comprising two symmetrical plates 5 and 6 which are spaced apart by spacers or filling pieces marked 7, 8, 9 and 10, see Figure 3. The two plates and the filling pieces are secured together in any suitable manner, such for instance as by rivets 11, and whereby there is formed a rectangular hollow base or body with rounded ends, which latter are made by bending the plates as at 12, 12.

The plates and the filler piece 8 are cut out and shaped to provide an opening or outlet 14 for the shavings which are planed off by the cutting or planing tool 15.

The latter has a stem 16 which passes between the plates 5 and 6, while the cutting end 15 is of a height equal to the height of the base as seen in Figure 2. The tool is therefore inserted into the body from the opening 14 and secured and adjusted by means of a wedge 17 which lies between the plates. The proper oblique direction to provide the correct cutting angle for the

tool is provided by shaping the ends 20, 20 of the filling pieces and by cutting the plates at an angle as at 21.

In this manner there is provided a hollow body or base having an oblique channel for receiving the tool and its securing wedge as shown, the channel communicating with the shavings outlet 14. The rounded edge of the latter is bevelled to both sides as indicated at 22.

The plates are provided with oblong holes 23 and 24, there being two pairs of these holes in alinement. The plane is operated by means of a detachable handle 25 mounted in two legs 26, 27. The one forward leg 26 has riveted thereto an oblong lug 28 on a stem 29. The other rear leg 27 has pivoted thereto a similar oblong lug 30 on a stem 31 which also carries a finger piece 32.

The handle is secured to the base by holding the handle at right angle to the base and inserting the forward lug 28 through the hole 23 in the plate 5, for instance, and then swing the handle into the position shown in Figure 2 to bring the lug 30 in over and in alinement with the rear oblong hole 24 in the upper plate.

The lug 30 is then pressed down through the hole 24 and rotated by means of the finger piece 32 so as to bring the lug 30 into the position shown in Figure 2 at right angles to the hole and under the plate 5.

The handle is now locked in position with both its lugs 28 and 30 at right angles to the holes 23 and 24 underneath the one plate 5. The handle is mounted in a position laterally inclined towards the cutting edge of the plane so that in operation pressure is automatically exerted on the tool in the cutting direction.

The plane is then used as shown in Figure 4 where it will be seen that the plane fits under the tongue 40 of the board 41 whereby to plane the lower edge 42 of the board, thus to insure that the adjacent grooved board, not shown, will fit tight against the upper edge 43 of the laid board 41.

When it is desired to plane in the opposite direction, the handle 25 is detached by turning the lug 30 into alinement with the

hole 24 and then lift it up over the plate 5. Then the handle is turned so as to permit the same operation at the forward hole 23.

The plane is then turned with the plate 6 uppermost as in Figure 3, the handle is again attached as described above and the plane is ready for planning in the opposite direction.

While I have disclosed my invention in its preferred form, nevertheless it will be understood that changes and alterations may be made in the details disclosed without departing from the intended and legitimate scope of the appended claim.

I claim:—

15 A tool of the character described comprising a flat body having vertical sides and a horizontal top and bottom, a cutting tool adjustably mounted in said body and projecting to the one side thereof in cutting position, a handle for said tool and means for detachably mounting said handle on either the top or the bottom of the body in a laterally inclined position whereby to automatically cause pressure to be exerted on the cutting end of the tool during the operation thereof.

OLE O. HAUGSBAK.
